UNITED STATES PATENT OFFICE

151,306

DESIGN FOR AN ALPHABET FOR FORMING
MONOGRAMS OR THE LIKE

Julius Weisman, Providence, R. I., assignor to
Plainville Stock Company, Plainville, Mass., a
corporation of Massachusetts

Application May 4, 1948, Serial No. 146,158

Term of patent 14 years

(Cl. D64—12)

To all whom it may concern:

Be it known that I, Julius Weisman, a citizen of the United States, residing at 74 Cathedral Avenue, in the city of Providence, county of Providence, and State of Rhode Island, have invented a new, original, and ornamental Design for an Alphabet for Forming Monograms or the like, of which the following is a specification, reference being had to the accompanying drawing, forming a part thereof.

Fig. 1 is a face view of an alphabet for forming monograms, showing my new design; and

Fig. 2 is an enlarged perspective view of one of the letters.

I claim:

The ornamental design for an alphabet for

forming monograms or the like, substantially as shown.

JULIUS WEISMAN.
